(57) **CLAIM**

The ornamental design for a cane stool, as shown and described.

DESCRIPTION

FIG. 1 is a front, right and top perspective view of a cane stool showing my new design;

FIG. 2 is a rear, left and bottom perspective view thereof; FIG. 3 is a front perspective view of the cane stool in an expanded state;

FIG. 4 is a rear perspective view of the cane stool in an expanded state;

FIG. 5 is a front view thereof;

FIG. 6 is a rear view thereof;

FIG. 7 is a left side view thereof;

FIG. 8 is a right side view thereof;

FIG. 9 is an enlarged top view thereof; and,

FIG. 10 is an enlarged bottom view thereof.

Broken lines in the drawing depict portions of the cane stool that form no part of the claimed design.
